*Primary Examiner—Melody N. Brown
Attorney, Agent, or Firm—Litman, McMahon and Brown,
L.L.C.*[57] **CLAIM**

The ornamental design for a weighted tarp, as shown and described.

DESCRIPTION

FIG. 1 is a top front perspective view of a weighted tarp, showing my new design;

FIG. 2 is a top plan view of FIG. 1;

FIG. 3 is a bottom plan view of FIG. 1;

FIG. 4 is a cross section taken along line 4—4 of FIG. 2 showing a curvate stock weight in place on the tarp;

FIG. 5 is a top front perspective view of a weighted tarp, showing a second embodiment of my new design;

FIG. 6 is a top plan view of FIG. 5;

FIG. 7 is a bottom plan view of FIG. 5; and,

FIG. 8 is a cross sectional view taken along line 8—8 of FIG. 6 showing a granular stock weight in place in the tarp.
